ATTORNEY

UNITED STATES PATENT OFFICE

ANTHONY H. COLLINS, OF BRONXVILLE, NEW YORK, ASSIGNOR TO CHICAGO PNEUMATIC TOOL COMPANY, OF NEW YORK, N. Y., A CORPORATION OF NEW JERSEY

MANUALLY-SUPPORTED POWER TOOL

Application filed April 3, 1928, Serial No. 266,965. Renewed August 4, 1930.

This invention relates to portable power operated percussive tools adapted to be manually supported and directed to the work. It has practical application to tools for hand 5 drilling and demolition work generally.

One object of the invention is to relieve the operator so far as possible of the shock and reaction of the tool when in operation. Another object is to protect the percussion motor 10 of such a tool from the destructive efforts of vibration. Other objects will be apparent from the detailed description which follows:

In order to illustrate the invention one concrete embodiment thereof is shown in the 15 accompanying drawings in which:

Fig. 1 is a vertical sectional view through the handle support and retainer portion of the tool showing the percussive motor also partially in vertical section, the parts being 20 in the inoperative or non-running position of the motor; and

Fig. 2 is a view similar to Fig. 1 showing the parts in the running position of the 25 motor.

In the embodiment of the invention chosen for the purpose of illustration, the tool comprises a cylinder 3 having an elongate axial chamber 3a in which is mounted for limited movement a percussive motor A, preferably 30 of the fluid pressure type. Cylinder 3 is arranged to be manually supported by aligned handles 4 which in the present instance are shown as forming part of a T head 5 which is secured to cylinder 3 in any suitable manner 35 as by bolts (not shown). Since motor A is indicated as of the fluid pressure type, head 5 preferably provides a connection at 6 for motive fluid and a throttle valve at 7, which is controlled by a lever 8 conveniently arranged 40 adjacent handles 4, the pressure fluid released by the throttle valve being directed into the rearward or handle end of chamber 3a.

Motor A has a head 9 slidably fitting the interior of chamber 3 and also has a reduced 45 portion or barrel 10 which extends beyond cylinder 3, suitable supporting and packing means being provided on the cylinder including packing ring 11, packing 12, and gland nut 13. Within the piston chamber of motor 50 A reciprocates a hammer piston 14 which is

controlled by an automatically thrown sleeve valve 15 moving in timed relation with the piston within a valve box 16 provided with a cap 17 held in place by a backhead 18, the latter having bores 18a therethrough to admit motive fluid from the rear end of chamber 3a to the motor. Packings 18 and 20 are arranged at opposite ends of motor head 9 and intermediate these packings the head is reduced by an annular groove providing a chamber 21 into which the percussive motor A exhausts.

The working tool or drill bit B extends into the barrel 10 of motor A to receive the blows of hammer piston 14 and is preferably formed with a collar b which not only serves to limit the extent of the bit shank within the barrel but also cooperates with a retainer 22 secured to the front end of cylinder 3 and of sufficient length to permit the movement of motor A within cylinder 3. Cylinder 3 has a series of radial exhaust ports 23 in a plane substantially centrally of chamber 3a.

Encircling the reduced portion or barrel 10 of the motor A and disposed within the annular chamber provided between the latter and the cylinder 3 is a coil spring 24 which bears against motor head 9 on the one hand and cylinder ring 11 on the other and normally maintains motor A inwardly of cylinder 3. To prevent motor A from striking head 5 when driven inwardly by the action of spring 24, suitable buffer means, such as a rubber annulus 25, may be provided in the rear end of chamber 3a to be contacted by motor head 18 and thereby limit the rearward movement of motor A.

In operation the opening of throttle valve 7 admits motive fluid to the rear end of chamber 3a, the motive fluid immediately becoming effective against the full area of motor head 18, with the result that motor A is driven forwardly in cylinder 3 against spring 24 (or cylinder 3 is driven rearwardly against such pressure as the operator may be applying to handles 4). When relative movement of motor A and cylinder 3 has reached the point where exhaust ports 23 register with exhaust chamber 21, percussive motor A goes into operation and con-

tinues in operation so long as it can exhaust through ports 23. To this end it is necessary that the operator apply sufficient pressure to handles 4 to balance, with the assistance of spring 24, the air pressure upon backhead 18 of the motor. When the throttle valve is closed and the pressure in the rearward end of chamber 3a vents to atmosphere through motor A, spring 24 moves motor A rearwardly or cylinder 3 downwardly until the motor is in inoperative position as disclosed in Fig. 1.

While a preferred form of the invention has been herein shown and described, it is to be understood that the invention is not limited to the specific details thereof, but covers all changes, modifications, and adaptations within the scope of the appended claims.

20 I claim as my invention:

1. A hand supported percussive tool comprising in combination a member having a handle and providing an elongate chamber, a fluid pressure percussive motor movable within said chamber, fluid pressure inlet means in said member adjacent said handle, the admitted pressure fluid being effective first to move said motor forwardly in said chamber and thereafter to operate said motor, and means wholly independent of the pressure fluid for opposing forward movement of said motor and for moving said motor rearwardly when the pressure fluid is no longer admitted.

35 2. A hand supported percussive tool comprising in combination a member having a handle and providing an elongate chamber, a fluid pressure percussive motor movable within said chamber, fluid pressure inlet means in said member adjacent said handle, the admitted pressure fluid being effective first to move said motor forwardly in said chamber and thereafter to operate said motor, means wholly independent of the pressure fluid for opposing forward movement of said motor and for moving said motor rearwardly when the pressure fluid is no longer admitted, and a resilient buffer for checking the rearward movement of said motor.

50 3. A fluid pressure tool comprising a cylinder member having a T handle and means including a throttle valve on said member for controlling the admission of pressure fluid to the chamber of said cylinder member, a fluid pressure motor movable as a unit within said chamber in one direction by the pressure fluid admitted thereto, means permitting operation of said motor by said admitted pressure fluid only when said motor is at a certain position within said chamber, and means for resisting movement of said motor by said pressure fluid and tending to maintain said motor at said certain operative position.

4. A fluid pressure tool comprising a cylinder member having a T handle and means including a throttle valve on said member for controlling the admission of pressure fluid to the chamber of said cylinder member, a fluid pressure motor movable as a unit within said chamber in one direction by the pressure fluid admitted thereto, means permitting operation of said motor by said admitted pressure fluid only at certain positions of the latter in said chamber, said means including one or more exhaust ports through said member, and means including a spring for resisting movement of said motor by said pressure fluid tending to maintain said motor at said certain operative position.

70 5. A fluid pressure tool comprising a cylinder member having a T handle and means including a throttle valve on said member for controlling the admission of pressure fluid to the chamber of said cylinder member, a fluid pressure motor movable as a unit within said chamber in one direction by the pressure fluid admitted thereto, means permitting operation of said motor by said admitted pressure fluid only when said motor is at a certain position within said chamber, and means wholly independent of said admitted pressure fluid for resisting movement of said motor by said pressure fluid and tending to maintain said motor at said certain operative position.

75 6. A fluid pressure tool comprising a cylinder member providing an elongate chamber and having a T handle, means including a throttle valve on said member for controlling the admission of pressure fluid to said chamber, a fluid pressure motor movable as a unit in said chamber by the pressure fluid admitted thereto, means permitting operation of said motor by said pressure fluid only at certain positions in said chamber including radial ports through said member, and means wholly independent of the pressure fluid for resisting movement of said motor by the pressure fluid and for moving said motor to a non-operative position within said chamber, said last named means comprising a coil spring encircling a portion of said motor within said chamber and arranged to be compressed by the movement of said motor by the pressure fluid.

80 Signed by me at New York, in the county of New York, and State of N. Y. this 31st day of March, 1928.
